CLAIM

The ornamental design for a stand for display screen as shown and described.

DESCRIPTION

1.1 : Perspective view of a stand for display screen

1.2 : Rear perspective

1.3 : Front elevation view

1.4 : Rear elevation view

1.5 : Left side elevation view, the right side view is omitted because it is a mirror image of the left side view

1.6 : Top plan view

1.7 : Bottom plan view

1.8 : Enlarged view taken from **1.1**

1.9 : Rear perspective view thereof in an environment

1.10 : Rear perspective view thereof in another environment

1.11 : Left side elevation view in an upward rotating state, the right side view is omitted because it is a mirror image of the left side view

1.12 : Left side elevation view in a downward rotating state, the right side view is omitted because it is a mirror image of the left side view

1.13 : Top plan view in another rotated state

1.14 : Front perspective view of the stand for display screen in a folded state

(Continued)

The evenly spaced broken lines immediately adjacent to the shaded areas depict the bounds of the claimed design, while all other broken lines are directed to environment. In addition, the dot-dash line and adjoining curvy line illustrate the bounds of the enlarged view and form no part of the claimed design. The broken lines form no part of the claimed design.
